CLAIM

The ornamental design for a chest, as shown and described.

DESCRIPTION

FIG. 1 is a front elevation view of a chest showing my new design;

FIG. 2 is a right side elevation view, the left side being a mirror image thereof;

FIG. 3 is a rear elevation view thereof;

FIG. 4 is a top plan view thereof;

FIG. 5 is a bottom plan view thereof;

FIG. 6 is a front elevation view of a second embodiment of the chest shown in FIG. 1;

FIG. 7 is a front elevation view of a third embodiment of the chest of FIG. 1; and,

FIG. 8 is a right side elevation view of the chest shown in FIG. 7 showing the drawer in extended position.

The top, bottom, sides and rear of the chests of FIGS. 6 and 7 are identical to those of the chest of FIG. 1 except for height.

The broken line showing of casters throughout the views is for illustration purposes only and forms no part of the claimed design.
